WILLIAM MARK WATSON, OF ST. CLOUD, FLORIDA

HYDRAULIC POWER DEVICE

Application filed June 15, 1931. Serial No. 544,657.

The invention relates to a power device of the hydraulic type and more particularly to a turbine rotor or water wheel type of such device.

5 The primary object of the invention is the provision of a power device of this character, wherein the turbine rotor or water wheel is submerged, preferably within a vertical casing such as a penstock and at the bottom 10 thereof whereby the weight of the descending water admitted to the upper end of the penstock augments the effect of the flow of the water against the rotor or wheel with resultant maximum of power obtainable from a 15 minimum supply of water.

Another object of the invention is the provision of a device of this character wherein the water is directed against equal arcs of the periphery of the rotor or wheel in the manner that its pressure is equalized to give perfect balance to the rotor or wheel throughout its continued rotative movement, as a consequence of which perfect balance is obtained and friction practically eliminated from the 25 moving parts of the turbine.

A further object of the invention is the provision of a device of this character wherein the penstock above the casing for the rotor or wheel will be supplied with an appreciable 30 amount of water as may be required to fill the entire penstock above the casing and which acts to greatly increase the pressure of the descending water and to concentrate the same directly at the peripheral intakes of the casing, these being symmetrically arranged 35 about the rotor or wheel periphery to effect the perfect balance thereof.

A further object of the invention is the provision of a device of this character wherein 40 means is employed having the form of one or more revolute planes and is connected with the rotor or wheel shaft at the mean level of the water as it enters the upper end 45 of the penstock from the sluice or other source of water supply and which will bear the weight of the shaft and the rotor or wheel on the surface of the water and acts on the latter when rotating with the shaft to effect an appreciable lifting effort on the shaft to 50 further reduce and minimize possible power

loss due to friction between the moving and stationary parts of the turbine.

A still further object of the invention is the provision of a device of this character which is comparatively simple in construction, thoroughly reliable and efficient in its operation, assuring maximum driving power with a minimum consumption of water and also inexpensive to manufacture and install.

With these and other objects in view, the invention consists in the features of construction, combination and arrangement of parts as will be hereinafter more fully described in detail, illustrated in the accompanying drawings, which disclose the preferred embodiment of the invention, and pointed out in the claim hereunto appended.

In the accompanying drawings:

Figure 1 is a vertical section through a device constructed in accordance with the invention and illustrating the preferred embodiment thereof.

Figure 2 is a sectional view on the line 2—2 of Figure 1.

Figure 3 is a sectional view on the line 3—3 of Figure 1 looking in the direction of the arrow.

Figure 4 is a sectional view on the line 4—4 of Figure 3.

Similar reference characters indicate corresponding parts throughout the several views in the drawings.

Referring to the drawings in detail, the device comprises a penstock 10 preferably in the form of a cylinder although it may be otherwise shaped and may be constructed from any suitable material, as for instance, heavy cast or steel metal. When constructed of metal it may be made in two or more sections suitably secured together by means of 85 nuts carrying bolts 11 to provide watertight joints between such sections.

Located interior of the penstock 10 at an elevation from the bottom thereof is a casing 12 preferably of cylindrical form and provides a casing or housing for a turbine rotor or water wheel 13 and this casing is of slightly less diameter than the interior diameter of the penstock so as to provide an annular 90 space 14 about the casing 12 between it and 100

the wall of the penstock 10. The rotor 13 is preferably bladed to form impact faces 15 disposed radially to its axis of rotation so that the water operates directly against the faces 15 and consequently in a plane parallel or substantially parallel to the first of the faces to be acted upon so that the water forces or strikes against the faces 15 with maximum pressure and without shock.

10 The peripheral wall of the casing 12 is formed to provide any number of intake ports or openings 16, two of such ports or openings being illustrated by way of example in the present instance. These intake ports or 15 openings 16 are to be equi-distantly spaced apart or diametrically opposite of the casing 12 and are formed by cut out portions 17 of the peripheral wall of said casing and which portions are preferably bent outwardly with 20 their outer edges in contacting relation to the wall of the penstock 10 in a manner to form vanes acting to direct the inflow of water inwardly of the casing 12 and against the rotor 13 as hereinbefore explained.

25 The bottom 18 of the casing 12 is provided with exhaust ports 19, one complementary to each of the intake ports 16 and disposed immediately in advance of the next succeeding intake port whereby with the two intake ports 30 16 as shown in the drawings, water entering these is effective for nearly one-half of the peripheral travel of the rotor or wheel 13 before being discharged outwardly of the exhaust ports 19.

35 A vertical shaft 20 is disposed axially and centrally of the penstock 10 and has its opposite ends projected through the bottom 18 of the casing and the top 21 of the penstock. This shaft is passed axially centrally through 40 the casing 12 and the turbine wheel 13, the latter being keyed at 22 to said shaft for rotation therewith. Rising from the top of the casing 12 and surrounding the shaft 22 is a tubular collar or stem 23 which has its 45 upper end terminating in a plane above the highest level of the water to be admitted to the penstock 10 so that the shaft 22 is not in contact with the water and hence any seepage of the latter downwardly about the shaft is 50 prevented. Also rising from the top of the casing 12 is a substantially conical-shaped element 24 preferably of hollow formation having the outer periphery of its larger end disposed flush with the outer peripheral wall 55 of the casing 12 and by which arrangement the flow of water through the penstock 10 is entirely free from obstruction. The upper smaller end of the element 24 is engaged about the tubular member or stem 23 at a 60 point immediately below its upper end.

Leading into the penstock 10 for the admission of water to the upper portion thereof through an opening 25 in the side wall thereof is a sluice or raceway 26, the latter being 65 equipped with a gate valve or other control

ling device 27 so that the inflow of water from the sluice or raceway to the penstock 10 can be readily controlled or regulated, the gate valve or other device 27 being manually operated from a hand turning wheel 28 accessible to the user of the device. Keyed or otherwise secured to the shaft 26 immediately above the upper end of the tubular column or stem 23 is the hub 29 of a blade carrier 30 to the under side of which are secured blades 31 which when rotated with the shaft 22 are arranged to operate on the water surface filling the penstock to the level of the inlet 25 in a manner to effect a lifting action on said shaft 22 and the turbine rotor or wheel 13. 70 The blades 31 are sheared substantially radially at points slightly offset one from the other diametrically thereof to form oppositely disposed flat portions which together constitute the plane of the device. The forward or leading edges 32 of the sheared portions of the blade 31 are curved slightly in an upward direction so that the inrush of water from the opening 25 will act against the inner or controlling sides of these curved portions and be deflected downwardly of the penstock 10 and its pressure will be exerted downward and against the flat under surfaces of the blades 31 to facilitate the sustaining of the weight of the shaft 22 and the rotor or wheel 13 carried thereby. The arms of the carrier 30 are angularly bent or curved so as to sustain the plane or blades 31 substantially in the level of the surface of the water when the penstock is filled.

100 The blades 31 are preferably of a very slightly less diameter than that of the interior diameter of the penstock 10, so as to have a maximum area of contact with the surface water therein.

105 Power is to be transmitted from either end of the shaft 22 in any suitable manner, as for example, through the medium of a bevelled gear 33 keyed on either projecting end of the shaft and this gear 33 meshes with a gear 34 on a power transmitting shaft 35 suitably hung or journaled for operation and from this shaft power is taken from the device.

110 Again with reference to the blades 31 at the upper portion of the penstock 10 which operate upon the water with a lifting force so as to relieve any end thrust of the shaft 20 and also the water wheel or rotor 13 at the bottom of the penstock which operates in its casing and 115 also constitute blades, these should be set at a pitch a little above that required by the discharge of water from the raceway 26 and also from the casing for the water wheel, thus making and causing an anti-friction bearing 120 which also by its operation adds its weight to the force of water downward causing a certain amount of power. The water by such action is forced forward on the wheel.

125 It is to be understood that the blades 31

do not at their impact side lie flat upon the water surface.

It is the purpose of this invention to receive all possible power from the water and in order to accomplish this the water has of necessity to strike at full force on the faces of the blades or the impact face of the water wheel as should be obvious.

What is claimed is:—

10 A hydraulic turbine comprising a vertically disposed cylindrical penstock having an inset bottom and a closed top, a sluice trough opening into the penstock near the closed top thereof, a shaft journaled centrally of the 15 penstock in the bottom and top thereof, pinions on the shaft outside of the bottom and top, countershafts journaled at right angles to said first named shaft and having gears meshing with the pinions, a water wheel with- 20 in the penstock and fixed to the shaft to be disposed next to the bottom, a housing within the penstock for the water wheel and of slightly less diameter than the interior diameter of the penstock and having tangentially 25 disposed intake ports diametrically opposite each other, a tubular column rising centrally from the housing about the first named shaft and terminating at its upper end in a plane above the highest level of water to be 30 admitted to the penstock, a conical element embracing the column for a major portion of its length and superimposed upon the housing, a hub keyed to the shaft next to the upper end of the column and having a blade 35 carrier, and radially sheared blades on the carrier and slightly offset, one from the other diametrically thereof to form oppositely disposed flat portions and having the leading edges of the shears curved slightly in an up- 40 ward direction, the carrier being slightly bent to sustain the blades substantially in the level of the surface of the water of the penstock when filled.

In testimony whereof I affix my signature.
